(57) **CLAIM**

The ornamental design for a bicycle dock, as shown and described.

DESCRIPTION

FIG. 1 is a front elevation view of a bicycle dock embodying my new design.

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front, and right side perspective view thereof;

FIG. 8 is a top, front, and left side perspective view thereof;

FIG. 9 is a bottom, front, and left side perspective view thereof;

FIG. 10 is a bottom, front, and right side perspective view thereof; and,

FIG. 11 is a top, rear, and left side perspective view thereof. The broken lines in the drawings illustrate portions of the bicycle dock that form no part of the claimed design.

1 Claim, 11 Drawing Sheets
